DESIGN FOR A COOK STOVE

Roebuck and Co., Chicago, Ill., a corporation
of New York

Application April 4, 1936, Serial No. 61,947

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Cook Stove, of which the following
is a specification, reference being had to the ac-
companying drawing, forming a part thereof.

The drawing is a perspective view of a cook
stove embodying my new design.

The shaded portion shown on the bottom of
the back splash panel represents a cavity to re-
ceive the lid shown adjacent thereto.

The appearance of the side of the stove not
seen in the drawing is similar to the side which
is shown.

I claim:

The ornamental design for a cook stove, as
shown and described.

JOHN R. MORGAN.
